UNITED STATES PATENT OFFICE.

EMIL GAIRING, OF CLEVELAND, OHIO.

BORING-TOOL.

1,214,773.

Specification of Letters Patent. Patented Feb. 6, 1917.

Application filed December 31, 1915. Serial No. 69,546.

To all whom it may concern:

Be it known that I, EMIL GAIRING, citizen of the United States, residing at Cleveland, county of Cuyahoga, State of Ohio, have 5 invented a certain new and useful Improvement in Boring-Tools, and declare the following to be a full, clear, and exact description of the same, such as will enable others skilled in the art to which it pertains to 10 make and use the same, reference being had to the accompanying drawings, which form a part of this specification.

My invention relates to boring tools and especially counterboring tools shown in the 15 accompanying drawings and more particularly pointed out in the following specification and claims.

One object of the invention is to provide means whereby a drill may be securely held 20 in its socket, not only when the tool is in operation, but against accidental release either while at rest or in operation; the construction being such, however, that it may be readily removed when required.

Another object of the invention is to provide means whereby the socket may be manually held while the tool is being driven that the tool may be removed from a chuck, (not 25 shown) or other driving means, while rotating, without risk of injuring the operator or of dropping the tool.

Another object is to provide for a positive driving relation between the pilot rod employed and the counterboring tool, as it is 30 well known that unless the pilot rod and the boring tool operate as a single unit, it is difficult, if not impossible to insure the counterbore being concentric with the hole which it surrounds.

Other advantages and improvements will 35 hereafter appear.

In the drawings accompanying this specification: Figure 1 is a longitudinal central section through the tool and its socket with 40 parts in elevation. Fig. 2 is a side elevation of the socket. Fig. 3 is a side elevation of the pilot rod. Fig. 4 is a longitudinal central section through the tool showing its central squared portion, adapted to interlock with the squared portion of the pilot rod. Fig. 5 is a perspective view of the tool 45 with the pilot rod in position. Fig. 6 is a cross-sectional view through the tool on line 6—6 of Fig. 4. Fig. 7 is a cross-sectional view on line 7—7 of Fig. 1. Fig. 8 is a cross-sectional view on line 8—8 of Fig. 1.

Referring now to the letters of reference placed upon the drawings: A, denotes a socket provided with a tapering shank A', adapted to be inserted in a suitable chuck or 60 other driving means (not shown.)

B, indicates a milled collar loosely sleeved upon the socket A.

C, denotes a retaining ring to secure the milled collar against lateral displacement, 65 and c, denotes a transverse pin to secure the ring to the socket.

D, designates a boring tool having a shank D', cut away at its end to provide a flattened surface D², adapted to slide past a 70 transverse pin E, supported in the wall of the socket A, upon entering the shank in the latter.

D³, denotes a groove formed in the shank D', opening into the flattened portion D², to 75 receive the transverse pin E.

A slight rotation between the boring tool and the socket in the direction in which the socket will be driven, will cause the transverse pin E, to enter the groove D³, thus 80 locking the tool in its socket.

D⁴, indicates a circumferential groove in the shank of the tool, designed to receive the movable detent F, supported in the wall 85 of the socket.

G, indicates a split resilient ring lodged in the groove formed in the periphery of the socket and also in a kerf in the detent F, adapted to force the latter into the groove 90 D⁴, in the shank of the tool.

H, denotes a pilot rod having an enlarged end H', adapted to be brought into contact with the end of the boring tool by means of a nut I, carried by the opposite screw-threaded end of the rod and in turn bearing 95 on the end of the tool shank. The pilot rod H is squared at H², to adapt it to enter a corresponding squared portion d, of the tool that the pilot rod and tool may be operated as a unit.

Having thus indicated the several parts by reference letters, the construction and operation of the device will be readily understood. When it is desired to remove tool and socket from the driving chuck (not shown), the milled sleeve of the socket is grasped by the hand of the operator while releasing it from engagement with the driving chuck. It will thus be obvious that while the tool and socket are rotating the sleeve may be 100 held by the operator and the tool and socket removed when the machine is still in opera-

tion. To withdraw the tool from the socket, following their removal from the driving chuck, the tool is manually given a slight reverse movement between the socket and the shank of the tool, whereupon the flattened portion D^2 , of the tool shank is caused to register with the transverse pin E , that it may be slid past the pin;—then upon slightly pulling the tool, the spring actuated detent F , is forced from its seat in the groove D^4 , and the tool is released. It will be obvious that when the shank of the tool is in the socket and being driven, the transverse pin E , upon entering the recess D^3 , will securely lock the tool in the socket; but should the tool through accident or otherwise, be caused to move with reference to the socket in a direction opposite to that in which the machine is being driven, the tool will not drop from the socket even though the flattened portion D^2 , may be in line with the transverse pin, as the spring actuated detent F , lodged in the groove D^4 , serves to hold the tool in its socket until manually released.

25 It will be clear that the pilot rod may be removed from the boring tool when not required for counterboring;—but upon entering the pilot rod in the boring tool, the nut engaging the rod is adjusted to secure the rod against lateral displacement;—while its squared portion will insure the operation of the pilot rod with the tool as a single unit.

Having thus described my invention, what I claim is:—

30 1. In a device of the character described, a socket member, a tool provided with a circular shank fitted to the socket member, a

short groove in the shank, a straight passage leading into said groove, a pin on the socket member for engaging said groove and locking the tool in the socket member, said straight passage permitting the pin to engage the groove, a second annular groove in said shank, a detent on the socket for engaging said annular groove, a circular spring for operating said detent, the said detent and annular groove forming means for retaining the tool in the shank in the event of the first named locking means between the tool and the shank becoming disengaged. 40 50

2. In a device of the character described, a socket member, a tool having a shank fitted to the socket member, means for locking the tool shank in the socket member upon rotation of the tool in the driven direction and unlocking said tool from said socket member upon rotation of the tool in the backward or reverse direction, an annular groove in said shank, a detent on the socket for engaging said annular groove, a circular spring for operating said detent, said detent and annular groove forming means for retaining the tool in the shank in the event of the locking means between the tool shank and socket member becoming disengaged due to the accidental turning of the tool in the socket in a backward direction. 55 60 65

In testimony whereof, I sign this specification in the presence of two witnesses.

EMIL GAIRING.
